WALL FORM CONSTRUCTION

Hayden C. Hill, Alhambra, Calif.

Application May 12, 1947, Serial No. 747,539

5 Claims. (Cl. 25—131)

1

My invention relates generally to demountable structures such as forms used in the erection of concrete structures and is concerned primarily with forms of a character suitable for providing a mold for shaping concrete poured during the erection of structural walls.

One object of the invention is to provide a form for poured concrete which includes a series of interlocking vertical panels adapted to be readily assembled in side-by-side relationship to obtain a form of required length, and detachable means for retaining the panels in this relationship and adequately reinforcing the same in their entire vertical and horizontal directions to effect maximum strength and rigidity.

Another object is to provide a demountable and interlocking form, of the character referred to, which is adapted for use in the erection of all flat, vertical concrete walls of predetermined and uniform thickness, and one which employs right-angled inside corner panels having relatively narrow sides for forming the right-angled intersections between adjoining walls, outside corner panels which are used in conjunction with the inside corner panels to form right-angled corners in a wall, and end panels adapted to be disposed across the ends of opposite parallel side panels in position to form the end of either an outer or inner concrete wall.

Another object is to provide a form of the type referred to in which several of the types of panels mentioned above are so proportioned in width that the algebraic sum of the width of a side wall panel and the proposed wall thickness has definite and consistent ratios between the width of a side or leg of an inside corner panel, between the width of a side or leg of an outside corner panel and between the width of a side or leg of an end wall panel. Since the widths of several of the types of panels are directly proportional to one and the same thing, that is the algebraic sum of the width of a side wall panel and the proposed width of the wall, they are directly proportional to one another and thus may be substituted, one for another, in forming concrete walls or partitions having right-angled turns, ells or extensions with positive assurance that the panels will properly interlock in erecting forms of various lengths and shapes. By this important provision, it is possible to assemble the form in such a manner that a concrete partition wall may be erected between parallel walls and at true right angles thereto.

Another object is to provide a demountable concrete form of the class indicated in which the panels are braced in a vertical direction by detachable studs and in which the side, corner and end wall panels are held in assembled relationship by horizontal wales, the lengths of the wales being directly proportional to wall panel widths,

2

so that the wales are interchangeable. By this provision, the lengths of the various types of wales are standardized in accordance with the widths of the different forms of panels and, therefore, proportional to an algebraic equation of the wall panel width and the thickness of the concrete wall to be poured, so that the wales may be applied to use for effectively connecting the panels together, regardless of the contour which the form is to follow.

Another object is to provide a demountable form of the type specified which is composed of a minimum number of interlocking parts adapted for economical fabrication from standard structural materials and one in which the several components may be readily set up or assembled at the site of the proposed building structure without the use of special tools or equipment.

Another object is to provide a demountable form comprising light weight panels adapted for easy handling and transporting and which may be quickly assembled to expedite the erection of the form and thereby reduce the cost of the structural walls to a minimum.

Further objects of my invention will be apparent from the following specification and the drawings, in which:

Fig. 1 is a perspective view of a section of a demountable form adapted to support poured concrete and the like and embodying the features of my invention;

Fig. 2 is a part-sectional plan view of a typical form assembly adapted to form intersections between right-angledly extending walls;

Fig. 3 is a part-sectional plan view of a typical form assembly adapted to form the corners of a building wall;

Fig. 4 is a part-sectional plan view of a typical form assembly adapted to form the end of a wall;

Fig. 5 is a cross-sectional view taken on line 5—5 of Fig. 2;

Fig. 6 is a plan view of a typical assembly of side panels, inside corner panels, outside corner panels and end panels, indicating the relation between the widths of these panels to each other and to the thickness of the concrete wall to be formed;

Fig. 7 is a view similar to Fig. 6 showing the relation between the lengths of the different types of wales and the widths of the different panels shown in Fig. 6.

Fig. 8 is an enlarged sectional view through the abutting edges of two adjacent side panels, showing the overlapping or interlocking thereof;

Fig. 9 is cross-sectional view taken on line 9—9 of Fig. 3 and illustrating the manner in which the wales are interlocked with portions of the panels to retain the latter in assembled relationship;

Fig. 10 is a fragmentary plan view of a portion of an inside corner wale;

Fig. 11 is a cross section, taken on line 11—11 of Fig. 10;

Fig. 12 is a perspective view of one type of wale used to connect a series of side panels;

Fig. 13 is a perspective view of another type of wale employed for joining a pair of side panels;

Fig. 14 is a composite perspective view of the inside and outside corner wales;

Fig. 15 is a perspective view of one of the wales used at the end of a wall;

Fig. 16 is a perspective view of a support or footing member used in conjunction with diagonal braces;

Fig. 17 is a part-sectional side view of one type of diagonal brace used on the improved concrete form;

Fig. 18 is a view of an alternative form of brace;

Fig. 19 is a perspective view of a portion of one of the vertical studs, showing the means for supporting a tie rod and two wales;

Fig. 20 is a perspective view of a clip element used for supporting a tie rod and side wall wales;

Fig. 21 is a cross-sectional view, taken on line 21—21 of Fig. 3; and

Fig. 22 is a fragmentary cross-sectional view through a hollow wall structure in which the panels are arranged in reverse position to locate the connecting elements within the wall.

My improved demountable or knock-down form for concrete wall structures comprises, in general, a plurality of side wall panels adapted to be stood on end with their vertical edges abutting to form a continuous planar surface, two such assemblies being arranged in spaced parallel relation to provide a channel or wall cavity therebetween for receiving concrete or the like which is poured thereinto to form the wall. Specially constructed inner and outer corner panels are employed for forming right-angular corners and the inner corner panels are also adapted for use in defining right-angular intersections between walls or partitions. End wall panels are also utilized for defining the ends of a wall or partition. The various types of panels referred to above may be assembled to provide forms capable of defining structural walls or partitions, or a combination of both, having right-angular turns or extensions. The assemblies providing the inner and outer sides or mold walls of the form are held in spaced-apart relation by means of tie-rods and by spaced vertical studs which have connecting portions overlying the top of the form. The individual panels of the structure are held in assembled relationship by means of horizontal rib-like members, commonly called "wales," which interlock with the panels. The horizontal wales and vertical studs thus serve to reinforce the panels and to retain them in proper connected relationship. The form is held in upright position by means of diagonal and horizontal braces or struts.

As a particular feature of improvement, my invention provides a combination of elements which are so proportioned that they may be readily interchanged, in assembling a concrete form or other structure, of desired configuration and size. That is to say, the algebraic sum of the width of the side wall panel and the width of the space between the facing sides of the inside and outside panel assemblies has definite ratios to the width of the legs of the inside corner panel, the outside corner panel and the width of the end wall panel. By this important provision,

the form is made more universal in application and the use of adjustable panels, connecting devices and substitute elements usually required in previous types of demountable forms is entirely avoided.

Referring to the drawings in detail, my improved demountable and knock-down form may assume various shapes, Fig. 1 showing the form erected in a manner so as to provide a mold and temporary support for a typical outer building wall and an inner extension thereof which may be regarded as an internal partition wall. Since it is desirable that the details of construction of the form be illustrated in relatively large scale, only a portion of the complete wall form is shown in Fig. 1, it being apparent that the form may be extended to provide a complete rectangular or irregularly shaped mold for the concrete or the like poured thereinto in erecting the outer walls and partitions of a house or other building. As shown most clearly in Fig. 1, the improved form consists of an inner mold wall 25 and an outer mold wall 26 which are arranged in spaced, parallel relationship to provide a wall cavity 27 therebetween for receiving concrete or the like which is poured into the cavity to form the wall of the house or other structure.

Each mold wall 25 and 26 includes a plurality of rectangular side-wall panels 30 which are disposed on end. Each panel 30 consists of a rectangular plate 31, preferably fabricated from sheet metal and referred to hereinafter as the sheathing, and reinforcing elements 32 attached to the plates adjacent their horizontal and vertical edges. The elements 32 preferably are in the form of angle-irons and thus provide projecting upper and lower horizontal ribs 33 and 34, respectively, and vertical side ribs 35 and 36. As shown in Fig. 8, one of the vertical elements 32 of each wall panel 30 is spaced inwardly from the vertical edge of the sheathing plate 31 while its other vertical element 32 is so disposed that it overhangs the other vertical edge of the plate 31. By this provision, when the wall panels 30 are placed in juxtaposition, that is with their vertical edges and ribs 35 and 36 abutting as shown in Fig. 8, the vertical seams between the sheathing plates 31 of adjacent wall panels are disposed out of alignment with the line of joinder between the abutting ribs 35 and 36. When the wall panels 30 are assembled in this manner, their sheathing plates 31 provide a smooth, continuous, planar surface for molding the poured concrete. The vertical ribs 35 and 36 of the wall panels 30 are provided with a plurality of vertically-spaced angular slots 38 having horizontal and vertical portions 39 and 40, respectively (Fig. 9), these slots being adapted to receive means, to be described hereinafter, for retaining the panels in assembled relationship. To facilitate dis-assembly of the side wall panels 30 after the poured concrete has set, I prefer to form the side of each angle-iron 32 having the rib 36, with an arcuate surface as indicated at 41 in Fig. 8 so that each panel may be pivoted outwardly away from the formed concrete wall and with respect to an adjacent panel. It will be observed, by reference to Fig. 5, that reinforcing elements 32' which extend along the lower edge of the panels 30 may be in the nature of Z-irons and the lower edges of the panels may be cut back to provide recesses 42 for receiving strips 43 which are mounted upon the foundation slab 44 upon which the concrete wall is to be erected, the strips being spaced apart at a distance corresponding with the thickness of the

proposed wall. The plates 31 of the wall panels 30 are provided with apertures 45 for the purpose to be presently explained.

Means are provided for reinforcing the inner and outer mold walls 25 and 26 and maintaining them in parallel, spaced-apart relationship. Referring to Figs. 1, 2, 5 and 19, stud units 50 assist in this purpose, the units including spaced, vertical studs 51 and 52 adapted to be disposed against the outer surfaces of the sheathing plates 31 of opposite side wall panels 30. Each of the vertical studs 51 and 52 consists of a pair of rectangular metal strips which are held in slightly spaced relation by means of spacer-rivets 54. Riveted between the upper end of the strips of one stud 51 is a horizontal element 55 adapted to extend transversely across the top of the wall cavity 27, the free end of the element having a vertical slot 56 cut in its upper edge (Fig. 5). After the stud 51 is placed against one of the side panels 30 of the inner mold wall 25 with its attached element 55 extending across the mold cavity 27, the other stud 52 is placed against the opposite wall panel 30, that is the panel of the outer mold wall 26, and its uppermost spacer-rivet 54 hooked into the slot 56 to connect the parts of the stud unit 50. Adjacent their upper and lower ends, the strips 51 and 52 are recessed, as shown at 58 and 59, to provide clearance for the ribs 33 and Z-irons 32 of the panels 30.

Angular, slotted brackets 60 are welded or otherwise secured to the studs 51 and 52 at vertically spaced point thereon (Figs. 1, 3, 5 and 19) and have vertical portions 63 abutting the outer edges of the studs and provided with square holes 64. When the stud units 50 are applied to the form structure in the manner previously explained, the holes 64 align with the apertures 45 of the side-wall panels 30 of the opposite mold walls 25 and 26 so that a tapered carriage bolt 65 may be inserted through each of the several sets of aligned holes and apertures, the bolts having square portions fitting in the square hole of the brackets 60 on the inner stud 52 and a threaded end projecting from the brackets of the outer stud 52. The bolts 65 serve as ties between the studs 51 and 52, nut-like handles 66 being screwed onto the threaded ends of the bolts to complete the fastening (Fig. 3). Additional tie-bolts 67 are also employed for the purpose of resisting outward forces exerted by the poured concrete against the side wall panels 30, these bolts being applied in the manner to be later explained. Spacer sleeves 68 may be employed on selected tie-bolts 65 and 67 to maintain the mold walls 25 and 26 in spaced parallel relationship as shown in Fig. 5.

In addition to being reinforced in a vertical direction by the stud units 50, the side wall panels are strengthened and held together in interlocking relation by means of metal strips or wales. Various types of wales are employed in the present improved concrete form, the wale 70 shown in detail in Fig. 12 being used to connect four successive side wall panels 30 of either mold wall 25 or 26. The wale 70 has three longitudinally spaced T-shaped slots 71 in one side thereof, these slots being spaced apart a distance equal to the center-to-center distance between successive abutting vertical ribs of the side wall panels 30. Extending across the narrow portion of each slot 71 is a transverse locking pin 72. In assembling the form structure, the wales 70 are first placed against the outer surfaces of four

successive side wall panels 30 with the pins 72 entering the horizontal portions 39 of the angular slots 38 in each pair of adjoining ribs 35 and 36 and the wales are then slid downwardly to dispose the pins in the vertical portions 40 of the slots, thus connecting the four panels 30 and providing lateral support therefor. The over-all length of each wale 70 is such that its ends terminate at the sides of successive stud units 50 as shown in Fig. 1 and rest upon a horizontal portion of the angular brackets 60. It is thus apparent that the several side wall panels 30 of the mold walls 25 and 26 are adequately reinforced in a vertical direction by their elements 32 and the vertical studs 51 and 52 and in a horizontal direction by the wales 70 which also serve to retain the panels in connected, interlocking relationship.

The wales 70 are provided with notches 75 in the same edge in which the slots 71 are located, one notch being disposed midway between each pair of slots as shown in Fig. 12. Each notch 75 is adapted to receive a vertical leg 76 of a U-shaped clip element 77, the horizontal portion of which underlies and extends transversely of the wale 70. The other vertical leg 78 of the clip element is slit and bent to provide lateral wings 79 adapted to snap over the outer edge of the wale to retain the element in place thereon. The legs 76 and 78 have aligned holes 80 and 81 which also align with the apertures 45 of the panels 30 and through which the carriage bolts 65, previously referred to, may be passed and secured in place by hand-nuts 82 as shown in Figs. 1 and 3. It is thus apparent that the mold walls of the form are effectively tied together to resist considerable strain and prevent bulging of the sides of the form.

The mold walls 25 and 26 may be braced externally by means of diagonal braces or props 85 (Fig. 1). Each prop 85 is preferably composed of two telescoping, tubular parts 86 and 87 having a series of spaced holes 88, any of which may be aligned to receive pins 89 which serve to retain the parts in longitudinally adjusted position. The lower part 86 has a slot 90 adjacent its lower end adapted to be hooked over a pin 91 carried by a footing element 92. The element 92 has a pointed vertical portion 93 (Fig. 16) adapted to be driven into the earth or into a wooden plank or the like extending lengthwise of the wall. The upper part 87 also has a slot 94 adapted to hook over one of the spacer rivets 54 between the strips of the stud 52.

The ends of the wall form are adapted to be closed by end wall panels 95 which are shown most clearly in Figs. 1 and 4. The end wall panels 95 are of U-shape in cross section, having opposite, parallel side members 96 connected by a transverse end member 97. The members 96 and 97 may be made from a single sheet of metal sheathing bent to the required shape. To the vertical edges of the side members 96 are secured angle-irons 98 which are adapted to abut the elements 32 of the side wall panels 30 when the parts of the form are assembled as shown in Fig. 1. The side members 96 and end member 97 of the end wall panel 95 are also provided with angle-iron reinforcing elements 99 at the upper and lower edges which form continuations of the corresponding elements 32 of the side wall panels 30, the elements at the lower edges being recessed to receive the locating strips 43.

The end wall panels 95 are held in connected relationship by means of U-shaped wales 100

which are shown in detail in Figs. 4 and 15. Each wale 100 consists of a pair of parallel members 101 which are pivoted to the ends of a connecting member 102 by means of rivets 103. The members 101 each have a T-shaped slot 104 provided with a transverse locking pin 105 adapted to be disposed in the angular slots 38 of the endmost side wall panel 30 and similar aligning slots in the reinforcing angles 98 of the side members 96. The wales 100 thus serve to strengthen the end wall panels 95 and retain them in assembled relationship.

As thus far described, the improved concrete form is adapted for use in making straight walls. It is within the concept of this invention, however, to provide means whereby the form may be erected in a manner to adapt it for use in forming concrete walls having right angular turns and extension, such an assembly being illustrated in Fig. 1. In order to produce the intersection between two right angularly related outside walls, I employ inside corner panels 110 and outside corner panels 111, the legs or sides of which are adapted to form continuations of the side wall panels 30 of the inner and outer mold walls 25 and 26, respectively. The inner corner panels have sheet metal sides or legs 112 which are adapted to align with the sheathing of the inner mold wall 25 to define the inner intersection of the angular concrete wall. The sides 112 are reinforced at their vertical and horizontal edges by angle iron elements 113 in a manner similar to that in which the side wall panels are strengthened, the vertically disposed elements having angular slots aligning with the slots 38 in the innermost side wall panels 30. To lock the inner corner panel 110 in position, I employ angular wales of the type shown at 115 in Fig. 14. Each wale 115 consists of a pair of right angularly related strips or legs 116 secured together by a rivet 117. Each leg 116 has a T-shaped slot 118 having a transverse locking pin 119 adapted to be inserted into the aligned, angular slots of the innermost side wall panels 30 and inner corner panel 110 to retain them in connected relationship.

The outside corner panels 111 comprise right angularly related sheet metal legs 120 adapted to provide extensions of the sheathing of side wall panels 30 of the outer mold wall 26 as shown in Fig. 1. The panels 111 have vertical reinforcing angles 121 adapted to abut the vertical elements 32 of the adjacent side wall panels 30 and horizontal angles 122 at their upper and lower edges, the vertical elements 121 having angular slots aligning with the slots 38 of the side wall panels referred to above. The outer corner panels 111 are locked in assembled relationship by means of outer angular wales 123, shown in detail in Fig. 14. Each wale 123 has a pair of right-angularly related legs 124 connected by a rivet 125. Each leg 124 has a T-shaped slot 126 provided with a transverse locking pin 127 adapted to engage in the angular slots in the abutting vertical edges of the side wall panels 30 and outer corner panel 111 to lock these panels together.

It will be apparent from the foregoing description and by reference to Fig. 1 that the inside and outside corner panels 110 and 111 cooperate in defining the inner and outer intersections of the proposed concrete wall and that they are positively locked in operative position by the wales 115 and 123.

It is sometimes desirable to form internal walls or partitions within the proposed building and it

is the usual practice to erect the forms of such walls during the construction of the outer wall forms so that all the walls may be formed during a single pouring of the concrete or like material.

5 The present improved concrete form is adapted to be assembled in a manner to produce such internal walls, such a wall or partition being indicated at 130 in Fig. 1. To assemble the form in a manner to obtain such an internal wall, it is 10 only necessary to omit one of the side wall panels 30 of the inner mold wall 25 and employ a pair of the inside corner panels 110 in its stead. The panels 110 thus define, between them, the intersection of the outer and inner walls of the building 15 and by adding the proper number of side wall panels 30 to the legs of the panels 110 the length of the internal wall or partition 130 may be established. As in the construction of the straight outside wall previously described, the end of the wall 130 may be defined by an end wall panel 95 and the several panels may be held together and reinforced by vertical stud units 50 and by the horizontal wales 70, 115 and 180. When the partition wall 130 is spaced relatively close to a 20 parallel portion of the outside wall, the use of a short wale 131 of the type shown in Fig. 13 may be necessary. Such a wale is of a length equal to the distance between stud units 50 positioned at adjacent side wall panels 30 and has a single 25 T-shaped slot 132 and locking pin 133 adapted to connect adjacent side wall panels. It is desirable that the portion of the form shown at 130 be externally braced and this may be accomplished by using props such as that designated 30 by the reference character 135 in Fig. 18. The prop 135 may consist of two telescopic members 136 and 137, each having a hooked end 138. A screw 139 carried by the member 137 may be tightened against the member 136 to maintain 35 the members in various positions of longitudinal adjustment. The ends of the members 136 and 137 may be hooked around selected spacer rivets 54 mounted on the stud units 50 of the outside and inside walls of the concrete form to brace the structure in the manner indicated at 140 in 40 Figs. 1 and 5. It is customary in forming concrete walls to employ reinforcing rods to add strength thereto. Such rods usually have their lower ends embedded in the concrete foundation and project upwardly therefrom to be embedded in the poured concrete wall. Referring to 45 Fig. 5, the present invention provides means for supporting the upper ends of such reinforcing rods 141, a clamping screw 142 being provided 50 on the horizontal elements 55 of each stud unit 55 for receiving and holding the rods.

As a particular feature of my invention, the widths of the various panels and the lengths of the different types of wales are proportioned in a 55 novel and unique manner so as to adapt the concrete form to be constructed in many ways and in accordance with the proposed contour of the wall. That is to say, the panels and wales are so substituted, one for another, in erecting the form to produce a structure of desired shape and size and, regardless of the manner of assembling the panels, the wales may be utilized for locking the panels in connected relationship. This desirable 60 result is attained by making the widths of the corner panels and the end wall panels, and the lengths of the wales in certain proportions of the algebraic sum of the thickness of the proposed concrete wall and the side wall panel. Referring 65 to Figs. 6 and 7 of the drawings, the important 70

and critical dimensions of the various types of panels and wales are designated by reference letters, the description and values of which are as follows:

A Width of wall panel, or $2B+C$, or

$$\frac{D(2B+C)}{E}$$

or

$$A=2E-C$$

$$A=\frac{Z+P}{N}$$

$$A=2Y+P+2Q-2B$$

$$A=2X+P-2D-2Q-2G$$

B Width of an inside corner panel leg, or

$$\frac{A-C}{2}$$

C Thickness of proposed wall

D Width of an outside corner panel leg, or

$$B+C, \text{ or } \frac{A+C}{2}, \text{ or } A-B$$

E Width of an end wall panel leg, or $=D$, or

$$B+C$$

F Over-all width of assembled form, or

$$=2S+2Q+C$$

G Width of any wale, or $=S$

N Number of panel junctions that wale Z is to engage

P Thickness of vertical studs

Q Thickness of sheathing

S Width of one vertical stud, or $=G$

W Over-all length of an end wall wale leg, or $=\frac{1}{2}A+E+G-\frac{1}{2}P+Q$

X Over-all length of an outside corner wale leg, or $=\frac{1}{2}A+D+G+Q-\frac{1}{2}P$, or

$$=Y-B+D+2Q+G$$

Y Over-all length of an inside corner wale leg, or $=\frac{1}{2}A+B-Q-\frac{1}{2}P$, or

$$=X+B-D-2Q-G$$

Z Length of any side wall wale, or $=(A \cdot N)P$

A study of the values outlined in the above table will show that some panels may be said to be interchangeable to permit the erection of forms of various dimensions and contours, as viewed from above. Moreover, by providing the wales of various lengths and shapes, they may be employed for connecting any selected panels in whatever order the latter may be assembled. For example, should the building plan specify a continuous, straight wall, having no partition or extension 130, a side wall panel 30 may be substituted for the inside corner panels indicated at 110' and 110" in Fig. 6 to provide a continuous inner mold wall 25. Likewise, whenever a right angle extension is required, one of the side wall panels 30 is omitted and a pair of the inside corner panels 110 substituted therefor to form the intersection, after which side wall panels and an end wall panel 95 may be added to the panels 110 to provide an extension of the proper length. As another example, the corner assembly indicated at 150 and the end wall panel 95 shown in Fig. 6 could be readily interchanged, if such a change was desirable. Since the widths of the several types of panels have constant relationships to the algebraic sum of the proposed wall thickness and the width of the side wall panels, the vertical edges of any of the panels of the opposite mold walls 25 and 26 always align transversely of the wall cavity and it is, therefore,

unnecessary to provide panels having other than these widths to attain this result. This is a highly desirable feature and an important improvement over previous types of demountable concrete forms wherein filler strips or adjustable elements are employed for obtaining such a condition. In the present improved structure, it is impossible to misalign the opposite wall panels of the inner and outer mold walls.

- 10 It is to be noted that the present improved form is designed for use in molding concrete walls of a particular standard thickness. As an example, if a wall of standard six inch thickness is to be produced, and A dimension is 16 inches, then B=5 inches, D=11 inches and E=11 inches. It will also be apparent that the present wall form is not intended to be adjustable for forming walls of different thickness and in this respect it is to be noted that if corner panel legs having widths other than standardized dimensions were used to provide wall cavities of different widths, it would not only complicate the assembly but require the use of special corner wales and other parts.

The method of assembling the wall panels to produce forms capable of molding concrete walls of various lengths and angular characteristics, and the mode of disassembling the parts after the forms have served their useful purpose should be apparent from the foregoing specification and thus need not be explained further.

It will be observed from the foregoing that my improved wall form is composed of simple, light weight parts adapted for economical manufacture from sheet metal and standard structural sections. Since the various parts are light in weight they may be conveniently transported and set up in the desired location. As another feature of improvement, the parts may be readily assembled without the use of special tools and equipment and in a minimum period of time and this results in a substantial saving in the cost of forming the concrete walls. Since the form is of a demountable or knock-down nature, it may be quickly dismantled after the concrete has set and its parts moved to another location and assembled to provide a form of the same or different shape. It is seen, therefore, that the improved form may be employed to great advantage in expediting the mass production of homes and other buildings.

It is within the concept of the present invention to employ the principle involved in erecting concrete forms to the building of hollow demountable wall structures which may be used in the construction of houses and other buildings. Fig. 22 shows such a hollow wall structure wherein the smooth sheathing surfaces of the various types of panels are disposed on the outside, instead of the inside, of the structure as in the embodiment of the invention disclosed in Figs. 1 to 21. By so positioning the panels, the walls have smooth outer surfaces, it being noted that the angle iron ribs 35 or 36 of the panels and the wales 70, are disposed within the wall cavity 160 which may be filled with a suitable thermal insulation material, if desired. The structure shown in Fig. 22 may be modified in other respects also. For example, since the side panels 30' are not subjected to lateral forces which tend to cause them to bulge outwardly, it is unnecessary to reinforce them from the outside and, therefore, the stud units 50' may be made of single strips of metal of a width corresponding to the wall cavity 160 so as to act as spacers between the opposite side panels 30'. The ends of the

wales 70' may be supported by the vertical studs 50' in the manner previously explained and their pins 72' are engageable in angular slots 38' in the ribs 32' of the wall panels 30'. In this embodiment, the slots 38' are arranged reversely, that is, with their vertical portions directed upwardly. By this construction, the several studs 50' and wales 70' may be assembled to provide a latticed framework, after which the wall panels 30' may be mounted thereon by merely hooking them over the pins 72'. It is thus seen that the combination of elements similar to those shown and described in connection with the concrete form may also be utilized for erecting demountable building walls or for pre-fabricating wall sections to expedite the construction of houses and other buildings.

While I have herein shown and described the improved wall form as embodied in a preferred construction and applied to use in a particular manner, by way of example, it will be apparent that various modifications might be made therein without departing from the spirit of the invention. Consequently, I do not wish to be limited to the exact embodiment shown but desire to be afforded the full scope of the appended claims.

I claim as my invention:

1. A demountable form for molding poured concrete and the like comprising: inner and outer spaced mold walls defining a wall cavity therebetween for receiving the poured concrete, each of said mold walls including a plurality of wall panels adapted to be disposed on end and each having a horizontal rib at its upper end and a vertical rib adjacent each lateral edge thereof, each of said vertical ribs being adapted to abut the vertical rib of an adjacent panel and provided with vertically spaced slots adapted to align with the slots of the adjacent panel; a plurality of reinforcing stud units each having vertical members adapted to be disposed against the outer surfaces of selected opposite wall panels of said mold walls and a horizontal connecting member extending across the upper end of the wall cavity, said vertical members also having slots for receiving said horizontal ribs of said wall panels; tie means for tying said vertical members of each stud unit together; and a plurality of horizontal wales adapted to span portions of at least two adjacent wall panels with their ends terminating at the sides of said vertical members of said stud units, said wales having longitudinally spaced means engageable in said slots of said wall panels to retain said panels in abutting relationship.

2. A demountable wall structure, comprising: a plurality of panels adapted to be stood on end and placed in abutting relationship; vertical reinforcing ribs secured to and extending adjacent to the vertical edges of each panel, the reinforcing ribs of adjacent panels being adapted to abut and each rib being provided with a plurality of vertically spaced angular slots; and horizontal wales having longitudinally-spaced slots each adapted to receive the abutting ribs of at least two adjacent panels and provided with locking pins engageable in said angular slots to lock said panels in connected relationship.

3. A demountable hollow wall structure, comprising: inner and outer spaced walls, each of said walls including a plurality of panels adapted to be stood on end and placed in abutting relationship; vertical reinforcing ribs secured to and

extending adjacent to the vertical edges of each panel, the reinforcing ribs of adjacent panels being adapted to abut and each rib being provided with a plurality of vertically spaced angular slots; a plurality of stud units disposed against the inner surfaces of two opposite panels and having portions extending between said panels for maintaining said panels of said walls in spaced, parallel relation; horizontal wales having longitudinally spaced slots each adapted to receive the abutting ribs of at least two adjacent panels and provided with locking pins engageable in said angular slots to lock said panels in connected, abutting relationship; and vertically spaced means on said stud units adapted to interlock with said wales to restrain said wales from horizontal or vertical movement.

4. A demountable hollow wall structure, comprising: inner and outer spaced walls, each of said walls including a plurality of panels adapted to be stood on end and placed in abutting relationship; vertical reinforcing ribs secured to and extending adjacent to the vertical edges of each panel, the reinforcing ribs of adjacent panels being adapted to abut and each rib being provided with a plurality of vertically spaced angular slots; a plurality of stud units disposed against the inner surfaces of two opposite panels, each stud unit having portions extending between said panels and vertically spaced retaining means; and horizontal wales having longitudinally spaced slots each adapted to receive the abutting ribs of at least two adjacent panels and provided with locking pins engageable in said angular slots to lock said panels in connected, abutting relationship, said retaining means being engageable with said wales to restrain said stud units from horizontal or vertical movement.

5. A demountable hollow wall structure, comprising: inner and outer spaced walls, each of said walls including a plurality of side wall panels, said inner wall including inside corner panels, and said outer wall including outside corner panels, any of said above named panels being adapted to be stood on end and placed in abutting relationship; vertical reinforcing ribs secured to and extending adjacent to the vertical edges of each panel, the reinforcing ribs of adjacent panels being adapted to abut each other; a plurality of stud units disposed against the inner surfaces of said walls to maintain the walls in spaced relationship; a plurality of side wall wales, inside corner wales and outside corner wales, each having longitudinally-spaced slots adapted to receive the abutting ribs of at least two adjacent panels and provided with locking pins for locking said panels in connected, abutting relationship.
